FIRE ESCAPE.

No. 406,257.

Patented July 2, 1889.

UNITED STATES PATENT OFFICE.

CORA A. BUTLER, OF CANTON, OHIO.

FIRE-ESCAPE.

SPECIFICATION forming part of Letters Patent No. 406,257, dated July 2, 1889.

Application filed November 26, 1888. Serial No. 291,919. (No model.)

To all whom it may concern:

Be it known that I, CORA A. BUTLER, a citizen of the United States, residing at Canton, in the county of Stark and State of Ohio, have 5 invented certain new and useful Improvements in Fire-Escapes; and I do hereby declare that the following is a full, clear, and exact description of the same, reference being had to the annexed drawings, making a part 10 of this specification, and to the letters and figures of reference marked thereon, in which— Figure 1 is an isometrical view. Fig. 2 is a view showing manner of attaching the braces and bars to the suspending-chains. Fig. 3 is 15 a front elevation showing the escape in proper position for use. Fig. 4 is a detached view of one of the braces. Fig. 5 is a view showing a modified form of attaching the braces and bars to the suspending-chains. Fig. 6 is 20 a detached view of one of the bars. Fig. 7 is a sectional view showing escape attached and suspended. Fig. 8 is a view showing the escape folded.

The present invention has relation to fire- 25 escapes; and its nature consists in the different parts and combination of parts hereinafter described, and particularly pointed out in the claim.

Similar letters of reference indicate corresponding parts in all the figures of the drawings.

In the accompanying drawings, A represents the suspending-chains, which are formed of strong metal and as light as possible, reference 35 being had to the amount of strength desired, and at the same time providing a fire-escape that will be safe. To the suspending-chains A are securely attached the braces B and the bars C. The braces B consist of four bars, preferably formed integral, and may be formed square or rectangular, or in the form of a trapezoid. The object and purpose of providing the braces is to throw or hold the outer bars of the braces away from the wall of a 40 building. These braces should be so adjusted on the suspending-chains that they will come between the windows, as illustrated in the drawings, and are so adjusted for the purpose of having the inner bars of the braces abut

against the wall. The bars C are so adjusted 50 that they will come opposite the windows below the window from which the escape proper is attached or thrown out of. The braces B and bars C are so adjusted on the suspending-chains A that they will form a ladder 55 when suspended.

In use, the chains A are securely attached to the hooks a, said hooks are securely attached to the wall at any desired point below the window, when the chains A are thrown 60 from the window together with the braces B and bars C, thereby forming a safe and convenient ladder, and at the same time setting the ladder proper away from the wall of a building.

It will be understood that the braces and bars should be formed of metal and as light as possible, reference being had to the desired amount of strength. In Fig. 5 a modified form of attaching the braces and bars to the 70 suspending-chains is shown, which consists of an extension or arm passed through one of the links of the suspending-chains and securely hooked or bent around the link.

It will be seen that by my peculiar and 75 novel arrangement I am enabled to provide a fire-escape that will be safe, strong, and at the same time quickly and easily adjusted for use.

In Fig. 2 a collar d' is shown, which is se- 80 curely attached to the suspending-chains A, one of these collars being located at each corner of the braces B, or each end of the bars C.

The escapes should be so located and ar- 85 ranged that the ones from the upper windows will not interfere with the ones from the lower windows when they are suspended for use. In the drawings two braces are shown between the windows; but a greater number 90 may be used, if desired.

Having now fully described my invention, what I claim as new, and desire to secure by Letters Patent, is—

In a fire-escape, the combination of the 95 suspending-chains A, the braces B, attached to the suspending-chains and adapted to abut against the wall of a building between

the windows, the bars C, attached to the outer suspending-chains and adjusted to come opposite the windows below the one from which the escape is suspended, and means for attaching the suspending-chains to the wall of a building, substantially as and for the purpose specified.

In testimony that I claim the above I have hereunto subscribed my name in the presence of two witnesses.

CORA A. BUTLER.
